(57) **CLAIM**

The ornamental design for a universal joint coupling, as shown and described.

DESCRIPTION

FIG. 1 is a front, bottom perspective view of a universal joint coupling, showing our new design;
FIG. 2 is a rear, top perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is an enlarged top plan view thereof; and,
FIG. 8 is an enlarged bottom plan view thereof.
